BY-PRODUCT COKE OVEN AND APPARATUS
FOR OPERATION OF THE SAME

Paul M. Pinckard, Battle Creek, Mich.

Application January 31, 1940, Serial No. 316,677

5 Claims. (Cl. 202—112)

This invention relates to high temperature carbonization by-product coke ovens and the manner of their utilization in the production of valuable by-products.

According to current practice in this field, the products of distillation rising from the coking chamber of an oven pass into the hot zone adjacent the roof and thence through the ascension or stand pipe for collection and treatment. It is well known that these distillation products contain a number of valuable constituents, prominent among which are the aromatic hydrocarbons. During the period from the year 1914 to 1919, it became almost universal practice in the operation of by-product coke ovens to maintain a hot top reaction zone in an effort to convert more of the paraffin constituents to aromatic compounds. In view of the known disadvantages of excessively hot top operation however, the practice was discontinued at the expiration of this emergency period.

In accordance with the present invention it is proposed to increase the yield of these aromatic hydrocarbons by imposing catalytic material in the path of portions of the issuing gases. Such catalytic operation has not been found to be practicable in conjunction with existing ovens since the temperatures encountered in their hot zones are excessive for the catalytic formation of aromatic hydrocarbons. As a matter of fact, catalytic treatment at these excessive temperatures would result in a break-down of a considerable portion of the products into elemental carbon and hydrogen. Moreover, the interposition of such catalytic material in the hot zone or stand pipe of existing ovens would tend to increase the back pressure and thereby produce an undesirable flow of gas from the oven to the flues which is not only wasteful of the gases themselves, but likewise appreciably cools the flues and renders the oven as a whole inefficient.

An arrangement of by-passes whereby the charging passages of an oven have been interconnected with the stand pipe by conduits extending through a cool zone in the roof has already been disclosed in United States Letters Patent No. 1,888,012, issued on November 15, 1932, to the present inventor. The primary object in that patent was to provide one or more cool by-passes for gases, whereby hot zone temperatures would be entirely avoided, once the gases entered the by-passes. The advantages set forth for the patented construction include a shorter time during which the richest gases remain in the hot zone; the elimination of extreme pressure caused

by faulty levelling; and a better distribution and discharge of gas, particularly when its volume is at a maximum and the distance from the charge to the roof is least, a condition encountered when the coking chamber has been newly filled. It was stated as probable, in the specification of the patent referred to, that less ammonia will be broken up into cyanides; that there will be less polymerization of benzol to naphthalene; and that cooler gas will be delivered to the gooseneck.

It is contemplated in accordance with the present invention that the principal advantages of the patented construction be utilized and in addition, that provision be made for the catalytic treatment of the distillation products passing through the relatively cool by-passes or conduits so as to produce greater yields of the particular aromatic constituents sought. This is accomplished by providing removable sections or man-hole covers in the roof of such an oven to afford access to such a conduit or conduits which may interconnect a plurality of charging passages or a charging passage and the stand pipe. Newly constructed ovens may be designed for the provision of such conduits between each pair of charging passages and between the stand pipe and the charging passage adjacent thereto. In adapting the invention to existing ovens however, for structural reasons it may be desirable to interconnect only certain of the charging passages with one another and/or with the stand pipe.

The production of increased yields of aromatic hydrocarbons in the distillation of coal is understood as involving the phenomenon of dehydrogenation of paraffins. In accordance with the operation of present day ovens, this dehydrogenation is believed to be induced in the hot zone to some extent without the benefit of catalysis. In accordance with the present invention, the yield of such aromatic products can be greatly increased by the use of dehydrogenation catalysts in one or more conduits provided in the relatively cool zone of the roof above the coking chamber. In some instances it is contemplated that the products of catalysis be returned to the hot zone prior to their discharge through the stand pipe. In other instances it is deemed preferable to discharge the products from the catalytic zone or zones directly to the stand pipe.

A more complete understanding of the present invention will follow from a more detailed description taken in conjunction with the attached drawings wherein:

Fig. 1 is a somewhat diagrammatic elevation of a coke oven embodying the present invention;

Fig. 2 is likewise a somewhat diagrammatic representation of a coke oven illustrating a modification;

Fig. 3 is a fragmentary elevation disclosing a means affording access to contact materials interposed in the path of distillation products; and

Fig. 4 is an elevation somewhat similar to Fig. 3 as applied to an oven embodying a cross over flue.

In the oven depicted in Fig. 1, the coking chamber 10 is represented as containing a charge of coal, the distillation products of which pass through the hot zone 12 intermediate the top of the charge and the roof 14. The ascension or stand pipe 16 carries off the distillation products discharged thereto through an enlarged mouth 18 and, in accordance with the present invention, through a by-pass or conduit 20. The oven is provided with the usual charging passages 22, of which there are four, each provided with a lid or cover 24 which is removed during a charging operation and restored during actual coking. These charging passages are interconnected by conduits 26 provided in the roof of the oven and through a relatively cool portion thereof well above the coking chamber. As already indicated, the ascension pipe is connected to the charging passage adjacent thereto through a conduit 28.

Each of these conduits 26 and 28 is designed to receive one or more baskets or cartridges 30 containing catalytic material. These catalyst cartridges are inserted through suitably designed openings 32 formed in the oven roof, which are closed during operation by covers 34 held in sealing relationship with the roof by means of clamping assemblies generally identified by the reference character 36.

In actual practice it has been found that in small ovens of 6 tons capacity, the temperature at the junction of the ascension pipe with the brick work is approximately 640° C. In larger oven of 13 tons capacity and upwards, the temperature at a corresponding point may be expected to be somewhat higher, say between 650° C. and 700° C. Accordingly, it will be preferable to arrange the conduits in constructions embodying the present invention near the upper portions of the oven roof and therein catalytically react the distillation products within the temperature range best suited for the formation of the aromatic hydrocarbon products desired. In their passage to the relatively cool portion of the roof the gases undergo a substantial temperature reduction, and it is therefore probable that the temperature at which they contact the dehydrogenation catalyst will be below the 650° C. to 700° C. already discussed. Since aromatic compounds are formed at temperatures as low as 350° C., and perhaps lower under certain conditions, it will be clear that the present invention need not be restricted to operation at any precise temperature, other than such temperatures as will result in the formation of aromatics.

By thus promoting the catalytic reactions at relatively low temperatures as compared with those prevailing at the hot zone, there will be no danger of thermal degradation of the paraffin products to hydrogen and carbon such as is known to commence slightly above 800° C. It is known of course that the products of distillation being so rich in hydrogen in coal carboniza-

tion processes, practically suppresses any decomposition of benzene.

Among the catalysts contemplated are alumina and titanium dioxide, chromium oxide prepared by the ignition of ammonium bichromate and the halides of aluminum and zinc.

In operation of the apparatus illustrated in Fig. 1 of the drawings, the distillation products rising from the hot zone 12 of the oven, will pass upwardly through the charging passages 22 to the conduits 26 and 28 into contact with the bodies for effecting catalysis, the products finally being discharged from the oven through the stand pipe 16.

The modification shown in Fig. 2 of the drawings represents the invention in its application to an existing oven. The roof of the oven is shown as supporting a pair of rails 38 over which the charging car is operated and accordingly, to prevent weakening the construction, conduits are not formed directly under these portions of the roof. Instead, the formation of the conduits interconnecting the charging passages and ascension pipe have been confined to those portions of the roof which are not directly under the rails. In this modification, gases passing from the hot zone will rise through the charging passage 38 into contact with the catalytic masses and then descend through the charging passage 40 to the hot zone and finally be discharged from the oven either through the charging passage 42 adjacent the stand pipe and over a second body of catalytic material, or directly through the stand pipe. Other gases will rise from the hot zone through the charging passage 42, over the contents of the cartridges for the increase of aromatic hydrocarbon constituents and be discharged through the stand pipe. As previously stated, there is little or no decomposition of benzene even where the products of the cool zone catalysis are returned to the hot zone, due to an excess of hydrogen present.

The fragmentary elevation depicted in Fig. 3 of the drawings is intended to illustrate in somewhat greater detail a suitable arrangement for affording access to the conduits for insertion and removal of the basket or cartridge containing the contact materials. The basket 30 is shown as provided with trays 44 arranged in a staggered manner to assure complete contact with the gases. The clamping assembly 36 may suitably include a yoke 50 extending transversely of the oven and having its ends hingedly or otherwise connected to the oven roof, and a head 52 carried at the end of a screw 54 threaded through the yoke and rendered adjustable by a handle or wheel 56. When the screw is advanced, the cover 32 is pressed into sealing relationship with the roof of the oven to close the opening 30 until removal of the cartridge for regeneration is desired.

Somewhat similar to the showing in Fig. 3 is that appearing in Fig. 4 of the drawings. In this case however the arrangement has been shown in conjunction with an oven having a cross over flue 58 such as is used in the Koppers oven, the presence of which renders it necessary to construct the conduits 26 in a slightly different manner. Since the cross over flues are relatively near the top of the roof, there may be in some instances insufficient clearance to construct the conduits entirely within the masonry of the roof. In such an event, the cover 32 and the conduit itself may be curved so as to provide a conduit of adequate size above the cross over flue. To

reduce the effect of hot gases passing through the cross over flue, a slab of heat resistant insulating material 59 may be interposed between the top of the flue and the bottom of the catalyst conduit 26.

It will be noted in all of the figures that at the intersection of a charging passage with one of the interconnecting conduits, the lower corners 60 are sharply beveled to insure against clogging of the conduits during a charging operation.

As a further precaution against clogging the conduits in the cool zone, butterfly valves 62 or the like may be arranged to close the conduits with respect to the charging passages during a charging operation and until the blowing of coal dust has abated. For convenience, these valves have been shown only in Fig. 4, but it will be understood that they are equally applicable to the other forms of the invention.

Whereas the invention has been discussed with respect to only a few of the possible modes of operation and constructions with which it is operative, its scope should be construed in accordance with the appended claims.

I claim:

1. In combination with a high temperature carbonization coking chamber and a standpipe connected therewith, a roof for said chamber provided with vertical passages for gases, by utilizing two inner and two outer coal charging passages for same, a pair of larry car rails supported by said roof between the inner and outer passages, said roof being provided with a conduit interconnecting said inner passages and a second conduit interconnecting said standpipe with the outer passage nearest thereto, said conduits being arranged through a relatively cool portion of said roof above said chamber and having sealing means in removable covers said conduits being intermittent of each other and of the rails to permit the return of gases to the hot zone to overcome radiation losses below optimum temperature range for formation of aromatics and installation without reducing supporting strength for larry car rails.

2. In combination with a high temperature by-product coking chamber and vertical heating walls therefor and a standpipe connected therewith, a roof for said chamber provided with a plurality of spaced coal charging passages and

5 with a horizontal passage interconnecting a pair of said coal charging passages and retaining a body of catalytic material in said horizontal passages, said coal charging passages being used as vertical passages for gas and being approximately of a diameter equal to the width of said chamber.

3. In combination with a high temperature by-product coking chamber and vertical heating walls therefor and a standpipe connected therewith, a roof for said chamber provided with a coal charging passage acting as a vertical uptake for gases and with a horizontal passage retaining catalytic material, said horizontal passage interconnecting said charging passage with said standpipe through a relatively cool portion of said roof, said charging passage being of approximately of a diameter equal to the width of said chamber and a removable cover above the horizontal passage for the ready insertion or withdrawal of said catalytic material, the proportions of the passages permitting a treatment of a maximum quantity of coal gas.

4. In combination with a high temperature by-product coking chamber and vertical heating walls therefor and a standpipe connected therewith, a roof for said chamber provided with a plurality of spaced coal charging passages spanning the chamber and with a horizontal passage 30 interconnecting a pair of said coal charging passages and a second horizontal passage connecting one of the coal charging passages with said standpipe, the horizontal passages retaining catalytic material in that portion of the roof best suited for the formation of aromatic compounds and removable sealing covers for access to said catalytic material.

5. In combination with a high temperature by-product coking chamber and vertical heating walls therefor and a standpipe connected therewith, a roof for said chamber having vertical spaced coal charging passages spanning the width of the chamber and a horizontal passage interconnecting said charging passages with said standpipe, the horizontal passage retaining catalytic material in that portion of the roof in which the temperature is best suited for the formation of aromatic compounds.

PAUL M. PINCKARD.
